Primary Examiner — Wan Laymon(74) Attorney, Agent, or Firm — Malik Drake(57) CLAIM

The ornamental design for a T-shirt, as shown and described.

DESCRIPTION

FIG. 1 is a front exploded view of a T-shirt showing my new design; and,

FIG. 2 is a front view thereof.

The broken lines showing the short-sleeve shirt and shorts, long sleeve shirt and slacks, and evening gown are included for illustrating environmental structure and form no part of the claimed design.
